KEYLESS TUMBLER LOCK

Filed July 12, 1949

UNITED STATES PATENT OFFICE

2,637,195

KEYLESS TUMBLER LOCK

William W. Hurtel, Los Angeles, Calif.

Application July 12, 1949, Serial No. 104,229

13 Claims. (Cl. 70—153)

1

This invention relates to a keyless tumbler lock, being an improvement upon the keyless lock patented to me August 27, 1946, Patent No. 2,406,332.

In the lock described in my said patent, in order to change the tumbler combination it is necessary to remove the back portion of the casing and substitute therefor another back, whereas in the preferred embodiment of the present invention it is only necessary to open up the casing and rearrange the tumblers and tumbler stops in order to produce a new tumbler combination. In the structure shown in the aforesaid preferred embodiment the aforesaid advantage is obtained by one of the side walls of the casing of the lock being provided with a series of internally projecting tumbler supports which project through cut-outs in the tumblers, and the tumblers normally gravitate to (or may be spring impelled to) positions wherein their movement is stopped or their weight supported by said projecting tumbler supports.

Among the objects of the present invention are, not only to improve the lock structure in the above mentioned particular, but also to simplify and lower the cost of manufacture of the casing and the tumblers and to simplify the assembling of the lock.

By the present invention there is also provided an improved carrier for the locking bolt, said improved carrier being so constructed that tumbler engaging stops thereon may be rearranged when it is desired to change the combination of the lock.

Still another object is to provide a means for operating the lock from the back or inner side of the door of a room so that there will be no likelihood of a person occupying the room being locked in.

In regard to lowering manufacturing costs, this is accomplished in one embodiment of the invention by providing the casing of the lock with a wall member which carries a sectional tumbler supporting flange from which the consumer to whom the lock is sold may break away some of the sections leaving such sections as required for making the tumbler combinations he desires. In another embodiment of the invention cost of manufacture is still further reduced, by the provision of a simplified, elongated locking bolt carrier with adjustable tumbler stops frictionally held in place thereon.

Another object of the present invention is to improve upon my aforesaid patented lock by providing a bolt retracting means operable by the one and same hand which the operator is

2

using selectively to move the proper tumblers to lock bolt releasing position.

Other objects, advantages and features of invention will hereinafter appear.

5 Referring to the accompanying drawings, which illustrates preferred embodiments of the invention,

Fig. 1 is a perspective view of the lock as it appears when mounted upon a door, a fragment of which is shown.

10 Fig. 2 is a front elevation of one of the embodiments of the device with the face plate and operating knobs removed, the tumblers all being held by gravity in the down or normal position, the lock in such case always being locked. In this view some interior parts are broken away, better to disclose underlying structure.

15 Fig. 3 is an exploded perspective view of a lock bolt retracting means manually operable inside the door.

20 Fig. 4 is a perspective view of a fragment of the sectional tumbler supporting flange located in the upper back portion of Fig. 2, it being understood that in Fig. 2 certain sections of said flange have been broken away by the user of the lock to produce the desired combination of tumbler supports.

25 Fig. 5 is a fragmentary cross section on line 5—5 of Fig. 2.

30 Fig. 6 is a perspective view separately showing the three different types of tumblers used in the lock.

35 Fig. 7 is a front elevation of the preferred embodiment of the invention with the face plate and the operating knobs removed, the tumblers all being held by gravity in the down or normal position wherein certain of them lock the bolt against retraction. In this view some parts are broken away better to illustrate underlying structure, and the casing is provided with a simple, straight top flange which can be manufactured at a lower cost than the flange structure shown in Figs. 2 and 4.

40 Fig. 8 is a perspective view of the bolt carrier shown in Fig. 7. In this view one of the adjustable tumbler stops is shown in full lines removed from the carrier: its attached position being indicated by dotted lines. Part of the bolt carrier is broken away to disclose structure that would otherwise be hidden.

45 Fig. 9 is a cross section on line 9—9 of Figs. 2 and 7, a fragment of the door being included in the view.

50 Fig. 10 is a cross section on line 10—10 of Fig. 7.

55 Fig. 11 is a fragmentary sectional view of the

3

thumb-operable locking bolt retractor, on line 11—11 of Fig. 12.

Fig. 12 is a fragmentary sectional view of said bolt retractor on line 12—12 of Fig. 11.

Referring in detail to the drawing, the embodiment of the invention which will first be described comprises a generally rectangular face plate 14, back plate 15 and fastening bolts 16 passing through corner portions of the casing to hold the two plates together and to attach the lock to the door 17. Suitable flanges are shown on said plates to close in the sides and the ends of the casing, said face plate 14 having along its upper edge a backwardly directed flange 14a, and along its lower edge an interrupted backwardly directed flange 14b. Said flange 14a overlies an inwardly directed top flange 15a of the back plate 15, said flange 15a having a downward extension 15b terminating in a backwardly directed lip portion 15c. Along its lower edge said back plate 15 has a forwardly directed interrupted flange 15d.

The flange portions 14b and 15d are cut away as shown in Figs. 1 and 5 to provide an opening 19 that affords manual access to the liftable tumblers described later. Also, as shown in Fig. 5 the front wall 14 is provided along the upper side of the opening with a backwardly curved lip 19a.

As more clearly shown in Fig. 4, the top flange portion of the back wall 15 of the casing comprises a series of sections separated by cuts 21 so as to enable the purchaser of the lock, by breaking away certain sections to leave selected sections which produce the desired combination of tumbler supports.

The locking bolt 22 is carried internally by a bolt carrier 23 in relation to which said bolt is longitudinally moveable. Said bolt carrier, separately shown in Fig. 8, forms a part of the shiftable locking means and comprises a channel shaped metal bar mounted in said casing with its open side directed horizontally and toward the back wall 15 of said casing.

Upon the long edge portion of the upper flange 24 and of the lower flange 25 of the bolt carrier is detachably and adjustably mounted a series of stop members 26, all shaped and dimensioned the same, and a double width stop member 27, carried by the lower flange 25. However, all these stop members may be identical as to size and shape, in which case two of them may be attached against each other to perform the function of the double width member.

Each stop member 26 is shown consisting of a resilient metal clip made of a short strip or strap of spring metal, or else these clips may be cut and formed from a previously provided piece of square stock tubing and then pressed into place upon the flange portion 24 and 25 of the bolt carrier 23. In making these clips the tube may be previously slotted, or each clip may be slotted after it is cut off. Each of the stop members 26 has a straight middle run 29 from one end of which extends at right angle a straight clamping jaw 30. From the opposite end portion of each member 26 extends a second run 31 terminating in an inwardly directed lip 32 which cooperates with the aforesaid jaw 30 to complete the clamping function when said clips are in the embracing, clamping relation to the edge portions of the bolt carrier 23.

When the clips or stop members 26 are manufactured by being cut off from square stock tubing, the newly cut off stops or clips will be of a more angular shape than shown in Fig. 8, but

4

the act of forcing them onto the flanges of the bolt carrier 23 will cause them to assume substantially the shape shown in this view, and when said clips are in place the back run 29, together with the adjacent portions of parts 31 and 32 of each clip, will form the required tumbler controlled stop means, at times preventing the retraction of the bolt and the bolt carrier, as will later be explained.

As viewed in Fig. 8 the bolt carrier 23 has a transversely extending flange 33 at its right hand end which has a substantially semicircular notch 34 to receive the stem portion 35 of the already mentioned locking bolt 22. Said stem 35 carries a head 37 against which operates the lock bolt extending spring 38, retraction of the bolt being effected when the flange 33 is caused to force said head toward the right from the position thereof shown in Fig. 2. The free end portion 15 of a swingable arm 40 (see Figs. 2 and 9) is positioned to act against said head 37, at times manually to retract the locking bolt independently of its carrier against the opposition of the spring 38. Said arm 40 is fixed to a sectional rock shaft 41 that carries axially at its inner end a cup-shaped part 42 turnably fitted over a bearing sleeve 43 struck from a rectangular mounting plate 44 abutted against the outer casing wall 14. Said plate 44 has flange portions 45 on three sides to hold it in place along with adjacent parts of the lock.

Said cup shaped part 42 carries a square shank 46 which forms a part of the already mentioned sectional shaft 41. Said arm 40 having through it a square aperture fitted onto said shank. Said square shank 46 fits into the next adjacent square sleeve section of the shaft structure 41 detailed in Fig. 3. This sectional shaft sleeve structure is provided to enable the user to accommodate the lock to doors of different thickness, only two of the square sleeve sections being used to accommodate the thickness of the door fragment shown in Fig. 9, the remaining two sleeve sections having been bro' en off and discarded. The break-off cuts 41a surround said sleeve structure but do not extend quite to the passage therethrough (see Figs. 3 and 9) enough intact material being left to insure the required strength when a plurality of the sections are used. A knob bearing member 48 is shown in Fig. 9 attached to the door 17. Through this member turnably passes a square outer section 49 of the shaft structure 41, said section being made a part of the knob 50, and its inner end portion fitting into the adjacent square sleeve of the sectional shaft structure. A washer 51 and retaining pin 52 complete this part of the structure.

The tumbler assembly used in the present invention differs from that disclosed in my aforementioned patent mainly in providing each of the tumblers in its midlength portion with a slot 60. With the slots 60 of the tumblers cooperate tumbler hanger means shown as tumbler supporting lugs or projections 61 which project into the casting from its back wall 15, preferably being struck out from said wall as shown in Fig. 10.

In each of the two illustrated embodiments of the invention there are shown, by way of example, three different types of tumblers, there being three tumblers 62, three tumblers 63 and one tumbler 64, the special tumbler 64 being shown in the right hand portion of Fig. 6. Of the three tumblers of the type 62 shown in the left hand portion of Fig. 6, each has a forwardly deflected upper end portion 66, preferably inte-

gral therewith, and at its lower end a forwardly directed angular end portion 67 with an outer upwardly extending part 68 which at times cooperates with the stops of the bolt carrier 32.

As to the other set of three similar tumblers 63, each tumbler is likewise provided with the flange portions 66 and 67, but in the tumblers 63 a much shorter extension 68x takes the place of said flange 68. Said tumblers 63 are also each provided with a downward extension 69 of each of their top flanges 66. The tumbler 64 differs from the tumbler 63 only that a portion 68a of the former tumbler is extended at one side of the tumbler so as to reach over into the same obstructing relation to the locking bolt carrier as the aforementioned part 69 of the tumbler 63. This feature is disclosed in my aforesaid patent.

In Fig. 2 one of the tumblers 63 is located at the left end of the tumbler series, and the tumbler 64 having the extension 68a is the second of the series. Continuing progressively to the right, the tumblers 62 and 63 alternate to the end of the series, seven tumblers being shown. Also the bolt carrier, as shown in its mounted position in Fig. 2, has its stop members 26 positioned as more clearly shown in Fig. 8. With the parts thus shown, in order to release the carrier and locking bolt therein the operator will raise the two tumblers at the left of the series (a tumbler 63 and the special tumbler 64), together with the fourth and sixth tumblers, the latter two being 63's. If, while performing this operation, the operator disturbs the position of any of the other tumblers, he will be unable to retract the locking bolt. The lower end portion 67 of each of the tumblers (shown exposed through the casing slot 19 in Fig. 1), will be sufficiently wide to accommodate a finger of the operator, so that he may lift any tumbler, or required set of tumblers, with his fingers, without displacing the adjacent tumblers.

In Figs. 1 and 10 is shown the knob 70 for retracting the bolt and bolt carrier when the tumblers are in the releasing position. Said knob is furnished with a stem 71 which extends through and works in a slot in the front wall of the casing and is attached to the bolt carrier 23.

In Figs. 1, 11 and 12 is shown a swingable bolt retracting member 73 which is operable by the thumb of that hand of the operator the fingers of which are holding the required tumblers in the bolt releasing position. Said swingable member 73 is carried by a rockable stud 74 having a squared inner end portion which carries an operating finger 75 which extends through a small opening in the bolt carrier 23 and into a depression in the locking bolt 22, so as to be in an operative relation to the bolt and bolt carrier.

Instead of being made from strap material the tumblers 62 and 63 may be made from stock bar material or from tubing of the correct size. In case bar metal or tubing is used the tumblers will be produced by cutting instead of by bending as is done with strap metal. When bar metal is used, the spaces underlying the flanges 68, 68x and 69 will be occupied by solid metal.

In the operation of the device, which is for the most part the same as that described for my aforesaid patented lock, with the tumbler arrangement shown in the drawing, normally the flange portions 69 of the three tumblers 63 and flange portion 68a of the tumbler 64 cooperate with the upper row of stops 26 (see Fig. 8), to prevent retraction of the locking bolt carrier and bolt therein, and the operator must know the

combination or he will not understand that the aforesaid combination of tumblers must be lifted to release the bolt. If the operator inadvertently or unadvisedly lifts any of the other tumblers, their lower flange portions will cooperate with the lower row of stops 26 to obstruct the retraction of the bolt.

The means shown in Figs. 2 and 9, operated by the knob 50, (said means not being shown in my aforesaid patent), may be used to unlock the door from the inner side thereof.

I claim:

1. In a keyless lock of the kind described, a casing, an elongated, at times longitudinally movable locking bolt carrier mounted in said casing, a locking bolt carried by said carrier and independently movable in a lengthwise relation thereto, a spring within said casing tending to project said locking bolt, the latter being given a retractive movement independent of said carrier by closing the door, said carrier consisting of a channel shaped metal bar mounted in said casing with its open side directed horizontally, said bar comprising a pair of flanges united by a web a series of stop clamps detachably supported in a friction tight manner on each of said flanges, said stop clamps being attachable in the desired adjusted positions to predetermine the tumbler stop combination, a series of elongated tumblers the individuals of which extend in a crosswise adjacent relation to the carrier to cooperate with said stop clamps and are movably mounted within said casing for selective manual longitudinal movement to adjust them to release said carrier to permit its retraction together with the locking bolt which it carries, and manually operable means carried by said casing to retract said carrier and bolt.

2. In a keyless lock of the kind described, a casing, an elongated, at times longitudinally movable locking bolt carrier mounted in said casing, a locking bolt carried by said carrier in a guideway provided therefor in the latter, a spring within said casing tending to project said locking bolt, the latter being given an independent movement by closing the door, said carrier consisting of a single strip of rigid material having longitudinal edge portions, a series of stop members secured to and adjustable longitudinally along said edge portions to predetermine the tumbler stop combination, a series of elongated tumblers the individuals of which extend in a crosswise adjacent relation to said carrier to cooperate with said stop members and are supported by said casing for selective manual longitudinal movement to adjust them to release the carrier to permit its retraction together with the locking bolt which it carries, and manually operable means carried by said casing to retract said carrier and bolt.

3. The subject matter of claim 2, and said casing having internal projections passing loosely through said tumblers to support them and guide their movement.

4. The subject matter of claim 2, and said casing having an upper wall portion with a downwardly and inwardly directed portion which forms a substantially horizontal ledge, certain of said tumblers normally being supported by said ledge.

5. In a keyless lock of the kind described, a casing, an elongated shiftable locking means mounted within said casing for longitudinal movement and including a locking bolt, stops carried by said locking means at spaced intervals

therealong, a series of tumblers mounted in said casing, said tumblers consisting of strips of rigid strap material and certain of them having each a horizontal top flange, said casing having in its upper part horizontal hanger flanges for said horizontal tumbler flanges normally to rest upon, said hanger flanges being deflected portions of a side wall of the casing and being divided into sections by cuts which enable the user selectively to break away and discard flange sections not required to support the desired combination of tumblers, said tumblers with horizontal top flanges being manually liftable by persons not familiar with the combination, from a non-obstructing to an obstructing relation to the stops carried by the aforesaid locking means, and means carried by said casing manually to shift said locking means to the unlocking position.

6. In a keyless lock of the kind described, the combination, with a locking member and a set of gravity controllable tumblers certain of which have horizontally extending upper end portions; of a lock casing having a side wall portion with a horizontally extending sectional top flange, in the assembled structure each section of said flange being positioned to form a seat for one of the aforesaid horizontally extending tumbler portions, the sections of said flange being partially divided by cuts which enable the user selectively to break away and discard flange sections not required to support the desired combination of tumblers, said tumblers with horizontal portions being selectively manually liftable by persons not familiar with the combination, to position a portion of the tumbler assembly in an obstructing relation to the retraction of the locking member.

7. In a keyless lock of the kind described, a casing, an elongated shiftable locking means mounted within said casing for longitudinal movement and including a locking bolt, said shiftable locking means having longitudinally extending edge portions, a series of stop forming clips mounted upon and individually adjustable along said edge portions, said clips consisting of straps of form retaining resilient material bent into an embracing, clamping relation to said edge portions, a series of elongated vertically disposed longitudinally movable tumblers mounted in said casing in a cooperative relation to said stop forming clips, and manually operable means carried by said casing to retract said locking means.

8. The subject matter of claim 7, and said stop forming clips being adapted for being successively cut off from a piece of square stock tubing.

9. In a keyless lock of the kind described, a casing, an elongated, at times longitudinally movable locking bolt carrier mounted in said casing, a locking bolt carried by said carrier and independently movable in a lengthwise relation thereto, said locking bolt being given its independent movement by closing the door, said carrier consisting of a channel shaped metal bar mounted in said casing with its open side directed horizontally, a spring within the casing positioned to project said carrier, stop means carried by the

open side portion of said carrier, a series of manually operable tumblers mounted within the casing in a cooperative relation to said stop means, said channel shaped carrier having a transversely extending end flange with a notch in it and said locking bolt having at one end a head carried by a neck which extends through said notch, and a movable part extending into the space alongside said neck, said part being mounted within the casing and being manually movable against the inner side of said head to retract said locking bolt independently of said carrier against the opposition of said spring.

10. The subject matter of claim 9, and said spring acting against the outer side of said head, and the inner side of said head at times acting against said end flange to extend the bolt and bolt carrier.

11. The subject matter of claim 9, and said part which acts against said locking bolt head being a swingable arm, a rock shaft to which said swingable arm is secured, and a turnable knob located outside of the casing and secured to said rock shaft.

12. The subject matter of claim 11, and said rock shaft comprising a longitudinal series of sections with cuts which partly sever adjacent sections so that by breaking out superfluous sections the shaft may be shortened to accommodate the thickness of a door through which it extends.

13. In a keyless lock of the kind described, a casing, an elongated, at times longitudinally movable locking bolt carrier mounted in said casing, a locking bolt carried by said carrier in a guideway therefor in the latter, a spring within said casing tending to project said locking bolt, manually operable means mounted upon said casing, at times to move said locking bolt independently of said carrier to the unlocked position, said carrier consisting of a single strip of rigid material having longitudinal edge portions, a series of stop members secured to and adjustable along said edge portions to predetermine the tumbler stop combination, and a series of elongated tumblers the individuals of which extend in a crosswise adjacent relation to said carrier to co-operate with said stop members and are supported by said casing for selective manual movement to adjust them to release said carrier for retraction together with the locking bolt which it carries, when said lock is in its mounted position upon a door said tumblers being accessible from one side of the door and said means for independently moving said locking bolt being accessible from the other side of the door.
